DESIGN FOR A COOKING STOVE CABINET

John H. Benson, Salem, Ohio, assignor to Mullins Manufacturing Corporation, Salem, Ohio, a corporation of New York

Application March 16, 1944, Serial No. 112,934

Term of patent 7 years

(Cl. D81—4)

To all whom it may concern:

Be it known that I, John H. Benson, a citizen of the United States, residing at Salem, in the county of Columbiana and State of Ohio, have invented a new, original, and ornamental Design for a Cooking Stove Cabinet, of which the following is a specification, reference being had to the accompanying drawing, forming part thereof.

The figure is a perspective view showing the

front, top and one side of a cooking stove cabinet, embodying my new design; the other side, not shown, is substantially like the side shown.

The characteristic features of the cabinet disclosed reside in the top portions shown.

I claim:

The ornamental design for a cooking stove cabinet, as shown and described.

JOHN H. BENSON.
